UNITED STATES PATENT OFFICE.

PHILIPP HAKE, OF HOBOKEN, NEW JERSEY, AND FRANZ OECHSLI, OF NEW YORK, N. Y.; SAID OECHSLI ASSIGNOR TO SAID HAKE.

ORNAMENTATION OF CARDS, &c.

SPECIFICATION forming part of Letters Patent No. 338,955, dated March 30, 1886.

Application filed January 21, 1886. Serial No. 189,350. (No specimens.)

To all whom it may concern:

Be it known that we, PHILIPP HAKE, of Hoboken, county of Hudson, and State of New Jersey, and FRANZ OECHSLI, of the city of New York, in the county of New York and State of New York, both citizens of the United States, have invented certain new and useful Improvements in the Ornamentation of Cards, &c., of which the following is a specification, reference being had therein to the accompanying drawings.

Our invention relates to the ornamentation of visiting-cards, invitations, dance-programmes, and analogous articles, its object being to produce an article that will be novel and unique and present a highly ornamental and attractive appearance, as will be more fully hereinafter described, and particularly pointed out in the claim.

20 In the annexed drawings, making a part of this specification, Figure 1 is a view of a card with its edges treated according to this invention; Fig. 2, an enlarged sectional view of one of the edges of the same, and Fig. 3 a view of the same cut on a bevel.

25 Our invention consists in first irregularly notching the edges of the article and then applying to such edges a coating of metallic coloring material or similar substance. By thus

making the edges "ragged," and by using a 30 variety of colors, an extremely novel and attractive article is produced. To still more beautify and increase the effect, the irregular notches may be cut on a bevel.

In the drawings, A indicates the card, and 35 a the metallic coloring material.

We contemplate manufacturing these cards, &c., in many different shapes—such as oval and diamond shape—and therefore do not desire to be limited in this respect.

40 Being aware that it is not new to simply notch and color the edges of such articles as herein mentioned, we do not claim such as our invention in this application; but

What we do claim, and desire to secure by 45 Letters Patent, is—

As a new article of manufacture, a card, invitation, or analogous article having a ragged or irregular edge, the same being coated with a coloring-matter, substantially as herein set 50 forth.

In testimony whereof we affix our signatures in presence of two witnesses.

PHILIPP HAKE.
FRANZ OECHSLI.
